Primary Examiner — Marianne Pandozzi(74) *Attorney, Agent, or Firm* — Sterne, Kessler, Goldstein & Fox P.L.L.C.(57) **CLAIM**

The ornamental design for a dispenser, as shown and described.

DESCRIPTION

FIG. 1 is a top, front, right perspective view of a dispenser showing our new design;

FIG. 2 is a front view thereof; and,

FIG. 3 is an enlarged view of FIG. 1 with most of the broken line subject matter removed for ease of illustration.

The uneven-length broken lines represent unclaimed boundaries of the claimed design. The unclaimed line features shown in even-length broken lines in FIG. 3, and also shown in other figures, form no part of the claimed design. The even-length broken lines showing the remainder of the dispenser are for environmental purposes only and form no part of the claimed design.
